STABILIZATION OF LIGHT HYDROCARBON
OILS AND PARTICULARLY PRESSURE DIS-
TILLATEJoseph K. Roberts, Hammond, and George W.
Watts, Whiting, Ind., assignors to Standard
Oil Company, Whiting, Ind., a corporation of
Indiana

Application February 19, 1930, Serial No. 429,658

7 Claims. (Cl. 196—11)

This invention relates to the stabilization of light hydrocarbon oils, and particularly to the stabilization of pressure distillates of hydrocarbon oils. The invention will be more fully understood by reference to the following description in conjunction with the accompanying drawing, which is an elevation, partly in section and somewhat diagrammatic in character, of apparatus suitable for carrying out the process of the present invention.

Referring more in detail to the drawing, a valved line 5 leads from any suitable source of pressure distillate produced by pyrogenetic conversion from hydrocarbon oils. It is preferred to pass the pressure distillate products directly from the fractionating step of the conversion process in which they are produced to the line 5. The pressure distillate products are, in practice, withdrawn from the fractionating step in the vapor phase. A heat exchanger 6 and a cooling coil 7 are interposed in the line 5. The line 5 discharges into a separating drum 8, preferably at the lower portion thereof. A valved line 9 provided with a pump 10 leads from the bottom of the separating drum 8 and discharges into a column 11 through one or more valved branch-pipes 12 at an intermediate point of the column. A by-pass 10^a may be provided in the line 9 around the pump 10. A heat exchanger 13 is interposed in the line 9.

The column 11 is provided substantially throughout its length with a plurality of suitable fractionating elements (not shown) which may comprise a plurality of plates, for example of the bubble-cap, or the disk and doughnut type. A line 14 provided with a pump 15 leads from the bottom of column 11 and is connected to valved lines 16 and 17. The line 14 is connected in series with the heat exchanger 6 and a second heat exchanger 18. The line 16 leads to the lower portion of the column 11, whereby regulated portions of liquid may be withdrawn through line 14, subjected to reheating in the heat exchangers 6 and 18, and returned to the column 11. The heating fluid for the heat exchanger 6 comprises the pressure distillate vapors entering the system through the line 5, while the heating fluid for the heat exchanger 18 may comprise, for example, a hot tar withdrawn from the pressure distillation process wherein the pressure distillate undergoing treatment was produced. The heating fluid may be passed through exchanger 18 by means of valved lines 19 and 20. The line 17 is provided with a pump 21 and a cooling coil 22, and discharges into the upper portion of a tower 23

through a valved branch line 24 connected to a distributor 25 mounted within the tower. A bypass 21^a may be provided in the line 17 around the pump 21. The line 17 is provided with a valved extension 26 beyond the branch-line 24, 60 whereby regulated quantities of the liquid withdrawn from the bottom of column 11 may be withdrawn from the system.

The top of the tower 23 is provided with a valved drawoff line 27. A valved line 28 leads 65 from the top of the separating drum 8 and discharges into the lower portion of the tower 23 and a valved line 29, provided with a pump 30 leads from the bottom of tower 23 and connects with the line 9 at a point intermediate the drum 8 70 and the heat exchanger 13. A by-pass 30^a may be provided in the line 29 around the pump 30. The tower may suitably be of the type ordinarily employed in absorption processes for recovering light hydrocarbon oils from gases, for example, 75 refinery or casing head gas.

A valved gas and vapor line 31 leads from the top of the column 11 to a cooling coil 32 which discharges into a suitable gas and liquid separator 33. The separator 33 is provided with a 80 valved gas and vapor drawoff line 34. The line 34 is provided with a suitable compressor 35 and a cooling coil 36, which discharges into a gas and liquid separator 37. A valved liquid drawoff line 38, provided with a pump 39, leads from the 85 bottom of separator 33 to the lower portion of separator 37. A valved-branch-line 40, provided with a pump 41, is connected to the liquid draw-off line 38, at a point intermediate the valve therein and the separator 33, and discharges into 90 the upper portion of the column 11.

The separator 37 is provided with a valved gas or vapor drawoff line 42 which is connected to the gas or vapor drawoff line 28 leading from the separating drum 8 to absorption tower 23. The 95 valve in line 42 preferably should be of the constant pressure regulating type. A valved liquid drawoff line 43 having a heat exchanger 44 interposed therein, is connected to the bottom of separator 37 and discharges into a column 45, through 100 one or more valved branch-lines 46 at an intermediate point of the column.

The column 45 is provided substantially throughout its length with a plurality of suitable fractionating elements (not shown) which may comprise a plurality of plates, for example, of the bubble-cap, or the disk and doughnut type. A valved gas and vapor line 47 leads from the top of column 45 to a cooling coil 48 which discharges 105 into a suitable gas and liquid separator 49. The 110

separator 49 is provided with a valved vapor or gas drawoff line 50, and a valved liquid drawoff line 51, provided with a pump 52 and which discharges into the upper portion of the column 45, whereby the condensate may be returned as reflux. The valve in line 50 preferably should be of the constant pressure regulating type. A line 53 provided with a pump 54 and a heat exchanger 55, leads from the bottom of column 45 and communicates with valved lines 56 and 57. The line 56 discharges into the lower portion of the column 45, whereby regulated quantities of the liquid in column 45 may be withdrawn therefrom, subjected to reheating in the heat exchanger 55, and returned to the column. The heating medium employed in the exchanger 55 may comprise any suitable fluid, for example, a hot tar withdrawn from the pressure distillation process wherein the pressure distillate being treated was produced. This heating fluid may be passed through exchanger 55 by means of valved lines 58 and 59. The line 57 discharges into the heat exchanger 44 provided in the line 43 leading from separator 37 to column 45, whereby the liquid flowing through line 43 is preheated before it enters column 45. A valved outlet line 60, provided with a cooling coil 61, leads from the heat exchanger 44, whereby regulated quantities of the liquid withdrawn from column 45 by means of lines 53 and 57 may be discharged from the system. A valved line 62 leads into the lower portion of the column 11 for passing steam through the pool of liquid in the bottom thereof.

In carrying out the invention, the pressure distillate is separated into gaseous or vaporous and liquid portions in a pressure separation operation. The liquid portions are separated into lighter and heavier portions in a rectification operation, the lighter portions being separately subjected to rectification at a pressure exceeding 75 pounds to remove any undesirable light constituents. The heavier stabilized product forms the major portion of the final product and after being subjected to a suitable refining operation, comprising, for example, a chemical treatment and rerunning to remove undesired heavy ends, this product may be blended with the liquid product resulting from the second rectifying operation to form a stabilized distillate product. The gaseous or vaporous portions which are separated from the liquid portions of the distillate in the said separation operation are subjected to an absorption operation to remove from them any constituents which are desired in the final distillate product. The absorption medium employed in this operation preferably comprises portions of the heavier liquid product resulting from the first rectifying operation. The liquid employed in the absorption operation is then returned to the rectifying process.

Referring more in detail to the operation, and more particularly as carried out in the apparatus shown in the drawing, the light hydrocarbon oil which is to be stabilized, and which may comprise, for example, a pressure distillate produced in a hydrocarbon oil conversion or cracking process, operating under a superatmospheric pressure, is forced through the line 5, heat exchanger 6 and cooling coil 7, and into the separating drum 8. The pressure distillate is preferably introduced into the line 5 in vapor phase and at substantially the temperature at which it was discharged from the fractionating column of the cracking process in which it was produced. It may be introduced under the same, or greater or less

pressure than that under which it was maintained in the fractionating column. It is preferred, however, to introduce it under a pressure of about 50 pounds, more or less. While flowing through the heat exchanger 6, the vapors impart a portion of their heat to the liquid from the column 11 withdrawn through the line 14, and certain of the heavier portions of the vapors are thereby condensed. If further cooling of the vapors is desirable, a cooling medium may be passed around the coil 7.

The uncondensed and the condensed portions separate within the drum 8, the former being passed through the line 28 to the lower portion of the tower 23, and the latter being passed through line 9, heat exchanger 13 and one or more branch-pipes 12 into the column 11. The column 11 may be maintained under a superatmospheric pressure, for example 35 to 40 pounds pressure. When operating at 35 to 40 pounds pressure, the liquid in the bottom of column 11 is maintained at about 275° F., more or less, although it is to be understood that with higher pressure conditions, the temperature of the liquid should be higher, for example, under a pressure of 185 pounds the temperature of the liquid should be around 450° F., more or less.

In column 11, some of the lighter portions of the distillate separate as vapors and gas while the portions remaining in the liquid phase flow downwardly through the fractionating elements therein. The proportion of vapors at the point of introduction depends, of course, upon the temperature to which the liquid was preheated in exchanger 13 and the pressure conditions. The down flowing liquid comes into intimate contact with vapor and gas passing upwardly through the column, and is subjected to fractionation. This ascending vapor and gas is given off by the body of liquid in the bottom of the column 11, which is heated by passing predetermined portions of it through heat exchangers 6 and 18 by means of the lines 14 and 16. Steam may be passed through this body of liquid by means of the pipe 62 to strip the lighter constituents therefrom, if desired. Thus, the lighter portions of the descending liquid are vaporized and the heavier portions of the ascending vapors are condensed and collected in the lower portion of the tower.

The uncondensed vapors flow upwardly through column 11 and come into intimate contact with a cooler liquid portion discharged into the upper end of the column 11 from the separator 33 by means of the line 40, whereby the necessary cooling for fractionation is secured. This cooler liquid comprises condensed portions of the fractionated vapors which are passed from column 11 through line 31 to condenser 32. The condensate and cooled uncondensed vapors are discharged into separator 33 wherein the uncondensed vapors, together with any gases are separated from the condensed vapor, the vapor and gases being discharged through line 34. The condensate is withdrawn through line 38 which connects with the line 40, the function of which has been hereinbefore described.

The gases and vapors from separator 8, which are discharged into absorption tower 23, flow upwardly through the tower 23 wherein they come into intimate contact with a cooler, downflowing liquid which cools them and absorbs desired heavier constituents thereof. This cooling and absorbing medium preferably consists of portions of the liquid withdrawn from the bottom of column 150

11 by means of line 14 and passed by means of lines 17 and 24 into the upper portion of the tower 23. This liquid is suitably cooled before it reaches the tower 23 by means of heat exchanger 13 and coil 22. The remaining portions of the liquid passed through line 17 are withdrawn from the system through line 26 and comprises the heavier stabilized product. The unabsorbed gases are withdrawn from the top of tower 23 through line 27 and the absorbing liquid, containing the absorbed constituents, is withdrawn from the bottom of tower 23 through line 29 and discharged into line 9, wherein it is mixed with the liquid portions passed from separator 8 into the column 11 through the line 9.

The uncondensed vapor and gas withdrawn from separator 33 through line 34 is forced under a substantial pressure by means of compressor 35 through cooling coil 36 wherein substantially all but the lighter gaseous portions are condensed. The condensate and cooled uncondensed vapors or gases are discharged into separator 37 wherein the gases together with any uncondensed vapors are separated from the condensate, the gases and vapor being withdrawn through line 42 and mixed with the gases or vapors passed from separator 8 into tower 23 through line 28. The condensate is admixed with the liquid portions passed from separator 33 to the separator 37 through line 38. The mixed liquids are passed from separator 37 through line 43, heat exchanger 44 and one or more branch lines 46 into column 45, the condensate being subjected to re-heating within the heat exchanger 44 by means of a suitable heating medium.

Upon being discharged into column 45, some of the lighter portions of the condensate may separate off as vapors and gases while the portions remaining in liquid phase flow downwardly through the fractionating elements therein. The proportion of vapors at the point of introduction depends, of course, upon the temperature to which the condensate was heated in exchanger 44 and the pressure conditions. The downflowing liquid comes into intimate contact with vapor and gas passing upwardly through the column 45, and is subjected to fractionation. This ascending vapor and gas is given off by the body of liquid in the bottom of the column 45, which is heated by any suitable means, as by passing predetermined portions of it through heat exchanger 55 by means of lines 53 and 56. Thus the lighter portions of the descending liquid are vaporized and the heavier portions of the ascending vapors are condensed and collect in the lower portion of the column 45.

The uncondensed vapors flow upwardly through column 45 and come into intimate contact with a cooler liquid portion discharged into the upper portion thereof from the separator 49, by means of the line 51, whereby the necessary cooling for fractionation is effected. This cooling liquid introduced into the upper portion of column 45 may consist of condensate from the vapor and gas which is passed through line 47 to condenser 48. The condensate formed in the coil 48 and the uncondensed fixed gas are discharged into separator 50 wherein the gas and condensate are separated, the gas being withdrawn from the system through line 50 and the desired proportions of condensate being withdrawn through line 51, to provide reflux cooling in column 45 for the fractionation operation therein.

Portions of the liquid withdrawn from column 45 through line 53 are withdrawn from the sys-

tem by means of line 57. The liquid is preferably passed through heat exchanger 44, for the purpose of imparting heat to the condensate flowing through line 43 into column 45, and is withdrawn therefrom through line 60 and cooling coil 61. 80

The liquid portions withdrawn from the bottom of column 11 through lines 14, 17 and 26 comprise the heavy stabilized fraction, while those liquid portions withdrawn from the bottom of the column 45 through lines 53, 57 and 60 comprise the light stabilized fraction. The gases withdrawn through lines 27 and 50 comprise fixed gases which are undesired in the final product. It is preferred to so conduct the operation that the gases separated within the column 11 comprise all hexane and lighter hydrocarbons, while that separated from the lighter portion in column 45 consists mainly of propane, ethane and methane. 90

In a specific operation, the following pressures may be suitably maintained in the apparatus: The separating drum 8 may be maintained under 50 lbs. pressure, the absorber tower 23 at from 40 to 45 lbs., the column 11 at from 35 to 40 lbs., and the column 45 between 75 and 200 lbs. and preferably at 190 to 200 lbs. Under these pressure conditions the following temperatures are suitable. The drum 8, about 75° F.; the absorbing fluid is introduced in tower 23 at about 75° F.; the liquid portions to be stabilized are introduced into column 11 at approximately 200° F.; the top of column 11 is maintained at about 120° F. and the bottom at about 275° F.; the separators 33, 37 and 49 are maintained at approximately 75° F.; the lighter liquid portions to be stabilized are introduced into column 45 at about 165° F.; the temperature in the top of column 45 is about 140° F., and the temperature in the bottom of column 45 is about 250° F. It will be understood that these temperatures may be varied depending upon the character of products desired, the pressures maintained within the various parts of the apparatus, and other factors of operation. 105

It is to be understood that the fluid absorbing medium, containing the constituents absorbed by it from the gases separated from the distillate, instead of being passed to the rectifying column in which the heavier stabilized liquid portion is produced from the distillate, may be passed to a separate rectifying tower operated under similar conditions. In such an operation, the overhead vapors from such separate rectifying column may be passed to the second rectifying tower of the system in which the main portion of the distillate is treated, or it may be passed to a separate column operating under conditions similar to the corresponding second rectifying column in the system in which the distillate is treated. The liquid condensate from each of the separate columns may be blended with the products from the columns of the principal system, the heavier stabilized portions, of course, being first subjected to a suitable refining operation. When a separate rectifying column is so used for stabilizing the gas absorbing fluid the stabilized fluid may be used alone in the absorption operation, or portions of the stabilized heavier portion from the principal rectifying column may be employed alone; or portions of the rectified products from each of such heavy fluid stabilizing columns may be used. 115

It is to be understood that the specific details of apparatus and method hereinbefore set forth are for the purpose of illustration, and are not 150

intended to be regarded as limitations upon the scope of the invention, except as contained in the following claims.

We claim:

5. 1. The method of stabilizing hydrocarbon oil pressure distillate which comprises subjecting the distillate to a rectifying operation under superatmospheric pressure wherein the lower boiling portions thereof desired in the final product together with gaseous lower boiling portions are vaporized, removing said vaporized portions whereby a stabilized heavier liquid product is produced which is substantially free of said lower boiling portions, cooling and condensing the desired low boiling portions thereby separating the gaseous portions from said condensed lower boiling portions, subjecting said lower boiling portions to a separate stabilizing operation under superatmospheric pressure, passing said separated gaseous portions and a portion of the stabilized liquid produced in said first stabilizing operation to an absorption operation wherein constituents of said gaseous portions desired in the final product are absorbed in said stabilized liquid, and passing the liquid containing the absorbed constituents of the gaseous portion to said first rectifying operation. 80
15. 2. The method of stabilizing hydrocarbon oil pressure distillates which comprises subjecting the distillate to a rectifying operation under superatmospheric pressure wherein the normally liquid lower boiling portions thereof desired in the final product together with normally gaseous lower boiling portions are vaporized, removing said vaporized portions whereby a stabilized heavier liquid product is produced which is substantially free of said lower boiling portions, condensing the said normally liquid lower boiling portions thereby separating the gaseous portions and the desired lower boiling portions withdrawn from said rectifying operation, subjecting the condensed desired lower boiling portions to a separate rectifying operation under superatmospheric pressure higher than that in the initial rectifying operation, passing the separated gaseous portions withdrawn from said first-named rectifying operation to an absorption operation wherein constituents of said gaseous portions desired in the final product are absorbed in a fluid absorbing medium, and passing the absorbing medium containing the absorbed constituents to said first-named rectifying operation. 85
20. 3. The method of stabilizing hydrocarbon oil pressure distillates which comprises subjecting the distillate to a rectifying operation under superatmospheric pressure of about 35 to 40 pounds per square inch wherein the normally liquid lower boiling portions thereof desired in the final product together with normally gaseous lower boiling portions are vaporized, removing said vaporized portions whereby a stabilized heavier liquid product is produced which is substantially free of said lower boiling portions, condensing the said normally liquid lower boiling portions thereby separating the normally gaseous portions and the desired lower boiling portions withdrawn from said rectifying operation, subjecting the condensed desired lower boiling portions to a separate rectifying operation under a superatmospheric pressure of between 75 and 200 pounds, passing the separated gaseous portions withdrawn from said first-named rectifying operation to an absorption operation wherein constituents of said gaseous portions desired in the final product are absorbed in a fluid absorbing medium, and passing the absorbing medium containing the absorbed constituents to said first-named rectifying operation. 90
25. 4. The method of stabilizing hydrocarbon oil pressure distillates which comprises separating the distillate into gaseous and liquid portions, subjecting the liquid portion to a rectifying operation under superatmospheric pressure wherein the normally liquid lower boiling portions thereof desired in the final product together with normally gaseous lower boiling portions are vaporized, removing said vaporized portions whereby a stabilized heavier liquid product is produced which is substantially free of said lower boiling portions, condensing said normally liquid portions of said vapors, thereby separating them from said gases subjecting said condensed lower boiling portions to a separate stabilizing operation also under superatmospheric pressure, passing a portion of the stabilized heavier liquid product of said first-named stabilizing operation and the gaseous products from said separating operation together with the separated gases from said first-named rectifying operation to an absorption operation wherein constituents of said gaseous portions desired in the final product are absorbed in said stabilized heavier liquid, and passing the liquid containing the absorbed constituents of the gaseous portions to said first-named rectifying operation. 95
30. 5. The method of stabilizing hydrocarbon oil pressure distillates which comprises separating the distillate into gaseous and liquid portions, subjecting the liquid portion to a rectifying operation under superatmospheric pressure wherein the normally liquid lower boiling portions thereof desired in the final product together with normally gaseous lower boiling portions are vaporized, removing said vaporized portions whereby a stabilized heavier liquid product is produced which is substantially free of said lower boiling portions, separating the normally liquid portions from the normally gaseous portions of said vapors subjecting said separated lower boiling portions to a separate stabilizing operation under superatmospheric pressure of between 75 and 200 pounds, passing a portion of the stabilized heavier liquid product of said first-named stabilizing operation and the gaseous product from said separating operation together with the separated gases from said first-named rectifying operation to an absorption operation wherein constituents of said gaseous portions desired in the final product are absorbed in said stabilized heavier liquid, and passing the liquid containing the absorbed constituents of the gaseous portions to said first-named rectifying operation. 100
35. 6. The method of stabilizing hydrocarbon oil pressure distillates which comprises separating the distillate into gaseous and liquid portions, subjecting the liquid portion to a rectifying operation under superatmospheric pressure wherein the normally liquid lower boiling portions thereof desired in the final product together with normally gaseous lower boiling portions are vaporized, removing said vaporized portions whereby a stabilized heavier liquid product is produced which is substantially free of said lower boiling portions, condensing at least a part of the normally liquid desired lower boiling portions of the vaporous portions removed from said rectifying operation and separating the condensate from the said gaseous portions, passing at least a part of the condensate to a separate rectifying operation maintained under a pressure 105
40. 75. 140. 145. 150.

of between 75 and 200 pounds wherein substantially all undesired gaseous lower boiling portions contained in the condensed portions are separated therefrom and a stabilized lighter liquid 5 product is produced, passing the gaseous portions from said separating operation together with uncondensed gases from said condensing operation and a portion of the heavier liquid product of said first-named rectifying operation to an absorption 10 operation wherein constituents of said gaseous portions desired in the final product are absorbed in said stabilized heavier liquid, and passing the liquid containing the absorbed constituents of the gaseous portions to said first-named rectifying 15 operation.

7. The method of stabilizing hydrocarbon oil pressure distillates which comprises introducing the distillate into a separating drum wherein the distillate is separated into gaseous and liquid portions, passing the separate liquid portion to a rectifying column maintained under superatmospheric pressure of about 35 to 40 pounds wherein the lower boiling portions thereof desired in the final product together with gaseous lower boiling 20 portions thereof are vaporized and a stabilized product is produced in said column, removing 25 both of said vaporous lower boiling portions and

subjecting them to cooling whereby the constituents thereof desired in the final product are condensed and thereby separated from the said gaseous portions, introducing the condensed lower boiling products into a second rectifying column maintained under a pressure of between 75 and 200 pounds wherein substantially all undesired lower boiling constituents of said low boiling products are vaporized and the desired products are collected in the final phase as a stabilized lighter product, removing said vaporous undesired constituents from the latter column and from the system, passing the gaseous portions from said separating drum and from said cooling operation, together with a portion of the heavier stabilized product from said first rectifying column, to an absorption tower maintained under superatmospheric pressure, wherein constituents of said gaseous portions desired in the final product are absorbed in said stabilized heavier product, and withdrawing from the absorbing tower the liquid containing the absorbed constituents of the gaseous portions and passing the same to said first rectifying column.
